UNITED STATES PATENT OFFICE.

ROBERT H. McCARTHY, OF MADELIA, MINNESOTA.

RAIL-JOINT.

1,111,484.

Specification of Letters Patent.

Patented Sept. 22, 1914.

Application filed June 27, 1914. Serial No. 847,727.

To all whom it may concern:

Be it known that I, ROBERT H. McCARTHY, a citizen of the United States, residing at Madelia, in the county of Watonwan and 5 State of Minnesota, have invented certain new and useful Improvements in Rail-Joints, of which the following is a specification, reference being had to the accompanying drawings.

10 This invention relates to an improved rail joint, and has for its primary object to provide an improved device of this character whereby the use of bolts and analogous fastening elements for holding the abutting 15 ends of rail sections together may be dispensed with.

15 The invention has for another object to provide a rail joint wherein the opposed ends of the adjacent rails are peculiarly 20 formed for interlocking engagement with each other, and key members adapted to co-operate with means upon the rail ends which will admit of expansion of the rails but effectually preclude their complete separation.

25 The invention has for a further general object to provide a rail joint which is extremely simple in its construction, and strong, durable and highly efficient in practical use.

30 With the above and other objects in view, the invention consists in novel features of construction, combination, and arrangement of parts as will be hereinafter referred to 35 and more particularly pointed out in the specification and claims.

35 For a full understanding of the invention, reference is to be had to the following description and accompanying drawing, in which—

40 Figure 1 is a perspective view illustrating a rail joint embodying the present invention; Fig. 2 is a horizontal longitudinal section; Fig. 3 is a transverse section; Fig. 4 is a detail perspective view of the opposed 45 ends of the adjacent rails; and Fig. 5 is a similar view of one of the key members.

45 Referring in detail to the drawing, 5 and 6 respectively indicate the opposed ends of 50 two rails which are to be coupled or joined together. The web of each rail is increased in thickness for a short distance from each end, as shown at 7, and one rail is provided in one of its end faces with a V-shaped recess or mortise 8 which extends from the 55 tread surface of the rail to the base thereof.

The opposed end of the other rail is provided with a V-shaped projection or tenon 9 which is adapted to be inserted in the mortise of said first named rail when the rails 60 are brought together. The under side of each rail head is provided with a longitudinally extending beveled or inclined shoulder 10 which is spaced from the base of the thickened portion of the rail web and is co- 65 extensive in length therewith. These beveled or inclined shoulders upon the opposite sides of the rail web extend in relatively opposite directions. The end of each thickened web portion 7 is provided upon opposite sides of the rail with vertically extending inwardly inclined shoulders 11.

12 designates the keys whereby the two rails are joined or locked together. Each of these keys is in the form of a long steel bar 75 of substantially triangular shape in cross section, said bar having the oppositely beveled faces 13 which are designed to co-operate with the beveled shoulders 10 upon the bottom of the rail head, and the beveled or 80 inclined longitudinally extending shoulders 14 which are formed upon the base of the rail upon opposite sides of the web. The key bar has a lug 15 integrally formed upon one end thereof, while the other end portion 85 of the bar is reduced in thickness as shown at 16 and is normally disposed out of the longitudinal plane of the body portion of said bar or obliquely inclined as clearly illustrated in Fig. 5 of the drawing. The 90 extremity of this reduced end portion of the bar is also formed with a lug 17 which projects from the same face of said bar as the lug 15. The distance between these lugs 15 and 17 is slightly greater than the distance 95 between the vertical shoulders 11 of the adjacent rails when the ends thereof are engaged.

Having above described the several structural features of my invention its operation 100 will be understood as follows: The ends of the rails are first brought together, the tongue or tenon 9 on the end of one rail being fitted into the recess 8 of the adjacent rail. The keys 12 are now inserted from 105 opposite directions and moved longitudinally between the upper and lower shoulders 10 and 14 of the rails upon opposite sides of the web portion. The reduced ends 16 of the keys project outwardly between the longitudinal shoulders 10 and 14. The lug 15 is 110 finally engaged with the vertical shoulder

11 on one of the rails and the outwardly projecting reduced end portion 16 of the key is then forced inwardly with a sledge or other tool so as to dispose the same in the 5 longitudinal plane of the key and in parallel relation to the rail web. The lug 17 on this reduced end of the key will therefore be positioned in line with the vertical shoulder 11 of the other rail. These key lugs 15 and 17 will effectually prevent a movement of the 10 connected rails sufficient in extent to admit of the movement of the tongue 9 completely 15 out of the recess 8. The rails may, however, expand and contract. In this manner it will be seen that I have produced a very serviceable and highly efficient rail joint, and one which may be produced at small manufacturing cost.

While I have above described the preferred form, construction, and arrangement of the several elements employed, it will be understood that the device is, nevertheless, susceptible of considerable modification therein, and I therefore reserve the 25 privilege of resorting to all such legitimate changes as may be fairly embodied within the spirit and scope of the invention as claimed.

What is claimed is:

1. In a rail joint the combination of the rail sections provided upon their abutting ends with interlocking means, each of said rail sections being provided with vertical shoulders upon opposite sides of its web, and keys adapted to be fitted between the head and base portions of the rails and each provided with a reduced obliquely disposed end portion, the opposite ends of each key

having lugs formed thereon, the lug on one end of the key being adapted for engagement with a shoulder upon one rail section and the reduced end portion being adapted to be forced inwardly against the side of the other rail web to dispose the lug thereon in line with the corresponding shoulder upon 45 said latter rail.

2. In a rail joint the combination of adjacent rail sections provided with interlocking means upon their abutting ends and each having a thickened web portion producing a vertical shoulder upon each side of the main rail web, the under side of the rail head and the base of the rail upon opposite sides of said thickened web portion being provided with longitudinally extending shoulders inclined in relatively opposite directions, and key bars each having oppositely beveled faces for engagement with the opposed shoulders on one side of the rail webs and provided with a reduced end portion obliquely inclined with respect to the body of the bar, the opposite ends of the key bar having lugs formed thereon, one of which is adapted to engage one of the vertical shoulders on one rail, the reduced end 65 portion of said bar being adapted to be forced inwardly into parallel relation with the rail web to dispose the lug thereon in line with the vertical shoulder of the other rail.

In testimony whereof I hereunto affix my signature in the presence of two witnesses.

ROBERT H. McCARTHY.
